DESIGN FOR AN AUTOMOBILE HOOD

William T. Downs, Detroit, Mich., assignor to
Evans Products Company, Detroit, Mich., a cor-
poration of Delaware

Application March 3, 1937, Serial No. 67,953

Term of patent 14 years

To all whom it may concern:

Be it known that I, William T. Downs, a citizen of the United States, residing in Detroit, in the county of Wayne and State of Michigan, have invented a new, original, and ornamental Design for Automobile Hoods, of which the following is a specification. Reference may be had to the accompanying drawing, forming a part of this specification, wherein:

Fig. 1 is a perspective view of an automobile hood including grilles embodying my design.

Fig. 2 is an enlarged perspective view of a portion of the structure illustrated in Fig. 1 showing in greater detail the structure of one of the grilles.

The dominant features of the design reside in the grille members as shown in solid black lines on the drawing.

I claim:

The ornamental design for an automobile hood, substantially as shown and described.

WILLIAM T. DOWNS.
